UNITED STATES PATENT OFFICE.

CHARLES L. FLEISCHMANN, OF WASHINGTON, DISTRICT OF COLUMBIA.

DUPLEX PEDAL MOTOR.

SPECIFICATION forming part of Letters Patent No. 230,411, dated July 27, 1880.

Application filed March 31, 1880. (No model.)

To all whom it may concern:

Be it known that I, CHARLES LOUIS FLEISCHMANN, of the city of Washington, in the District of Columbia, have invented a new Mechanism called the "Duplex Pedal Motor," for working sewing-machines, of which the following is a specification.

The common treadle now in general use has to overcome with an exceedingly short leverage the weight and friction of the various parts of the sewing-machine—for instance, first, the foot-plate of the treadle; second, the pitman; third, the crank; fourth, the large band-wheel; fifth, the small band-wheel; sixth, the fly-wheel; seventh, the gearing and all the moving parts of the sewing-machine proper, and, finally, the material which has to be made up. All those various parts are lifted and depressed with a leverage of six inches for the toe part and six inches for the heel part of the treadle.

Now, when we consider that almost all sewing-machines are worked by females, whom nature has allotted less muscular power and a very short foot, with which they are not able to span the foot-plate of a treadle, we can easily understand the general complaints against the working of sewing-machines. Yet all the above-enumerated parts are indispensable to obtain the necessary speed and action in sewing-machines, and any alteration in sewing-machines as to the weight or size of any one of the specified parts does not remedy the existing difficulties. It requires a radical change to remove the objections, and my improvements have the object to make that change—first, by an increase of leverage, and, second, by a considerable decrease of the foot motion. I attain these objects by the mechanism illustrated in the accompanying drawings, in which—

Figure 1 is a perspective view of the rocking lever, showing the mode of attaching the pedal-rods thereto and the position of the foot-rest. Fig. 2 is a detailed view of the rocking lever and the pedal-rods. Fig. 3 is a side view of the rocking lever, the pedal-rod, and the foot-rest.

Similar letters refer to similar parts throughout the views.

The rocking lever A, having its fulcrum at

B, is about one foot long, and has at one end the pitman C attached to it. About two or three inches from each side of the fulcrum B are the pedal-rods D E, suspended. They act 55 separately upon the rocking lever A, describing shorter segments of a circle than the ends of the lever A. The rocking motion which the pedal-rods have in common with the lever A diminishes gradually and becomes almost 60 nought at F F', where the pedal-rods turn in sockets. The pedal-rods are from twenty to twenty-four and more inches in length, and they exert considerable leverage at the rocking lever A, so that that lever requires little 65 power to raise or depress it, and it is easy to calculate how much less power it takes to work the rocking lever A and its appendages with twenty-four-inch levers instead of with six-inch leverages as is the case in the common 70 treadle.

At the rocking lever A the pedal-rods D E are from four to more inches apart, and they run parallel with the foot-rest G, upon which the foot is placed to work the pedal-rods. 75 The foot rests with the toes on the pedal-rod E, the heel on the pedal-rod D. The foot-rest G is placed about half-way between the rocking lever A and the socket at F F'.

Instead of the foot-rest, a treadle may be 80 used in place of it, which overlaps with its ends both pedal-rods. When the foot depresses or raises one of the pedal-rods it produces a rocking motion of the lever A. This motion gradually decreases along the pedal-rods D E, and as it approaches the sockets F F' it almost ceases. At half the length of the pedal-rods the rise or fall of said rods is only about one inch, and it is there where the foot is placed to operate the pedals. To elevate 85 the foot one inch and depress it one inch require scarcely any effort, and that slight motion neither causes strain on the foot nor produces any injurious consequences, as is the case with the common treadle. In a machine with a common treadle, working a two-inch crank, the ends of the treadle have to be raised four inches and depressed the same number of inches, so that at every revolution of the crank the treadle motion amounts to 90 eight inches, whereas in the duplex pedal motor the foot has only to be raised one inch

and depressed another inch, making at every sweep of the crank a saving of about seventy-five per cent. of foot motion over the treadle motion.

5 It is obvious that the duplex pedal motor can be worked with considerable less power and with an increased gain of fast motion, and a person even at a tender age can work the sewing-machine without experiencing any 10 one of the injurious consequences the common treadle is liable to produce.

The duplex pedal motor can be worked twice as fast in the same space of time as the common treadle now in use, it requiring only 15 a tap with the toes and heel of the foot to pro-

duce an entire revolution of the crank; whereas a treadle has to move through four times the space before the crank has made a complete sweep.

What I claim as my invention, and desire 20 to secure by Letters Patent, is—

1. The combination of the lever A and the pedal-rods D E, substantially as described.

2. The combination of the lever A and pedal-rods D E with the foot-rest G, or its equivalent, substantially as set forth. 25

CHARLES LOUIS FLEISCHMANN.
